FIRE RESISTANT STUDS

Henry P. Caligiuri, 241 E. 137th St., Bronx, N.Y.
Filed Mar. 12, 1963, Ser. No. 264,513
2 Claims. (Cl. 189—34)

This invention relates to studs used in the preparation of room dividers and partitions. More specifically it relates to studs that eliminate transmission of flame and smoke from one room to another.

In conventional partitions between rooms in factories, salesrooms and the like, slotted studs are used in vertically disposed position in lieu of the conventional lumber 2 by 4 of the building trade.

The studs for formation of conventional partition walls are made of sheet metal and are of rectangular two inches by four inches in cross-section. These studs are provided with at least one row of linearly disposed apertures of suitable rectangular configuration on each of the four faces. The slots on the narrow face of the studs are exposed to the atmosphere between the dry wall and are used to engage the hooks of hangers used for display shelves and the like.

A serious disadvantage of these slotted steel studs are that they permit atmospheric communication between the rooms through the slots located on the opposed narrow faces of the stud. Thus where there is a fire in one room and hence on but one side of the partition, smoke and even flame can pass through these apertures of the stud into the adjoining room.

It is an object of this invention to provide an apertured fire resistant metal stud that prevents transfer of smoke and flame therethrough.

It is a further object to provide a hollow longitudinal stud of a rectangular cross-section having at least one removably disposed linear firewall therein.

It is another object to provide an apertured all metal hollow stud having non-apertured sheet metal panel means suitably disposed therein to prevent passage of smoke and flame through said stud.

It is another object of this invention to provide a hollow linear stud of rectangular cross-section, each of whose four walls are provided with a plurality of apertures, having a separate slideably insertable non-apertured planar firewall disposed substantially hermetically therein thereby preventing atmospheric communication between opposing walls.

These and other objects of this invention will become apparent upon reading the following descriptive disclosure of several embodiments thereof and as shown in the accompanying drawing in which:

FIG. 1 is a perspective view of a rectangular metal stud having a separate sheet metal firewall or tongue slideably disposed diagonally therein,

FIG. 2 is a cross-section view of a modified stud having a zig-zag firewall slideably disposed diagonally therein,

FIG. 3 is a cross-section of another modified stud having a step type firewall therein,

FIG. 4 is a cross-section of yet another modification of this invention showing a pair of substantially U-shaped sheet steel elements disposed therein, said elements having planar contact at the base of each of the U-shaped panel elements,

FIG. 5 is a cross-section view of another modification, being a modification of the firewall of FIG. 4 altered to provide for insertion of hooks of lateral in-between wall elements,

FIG. 6 is a cross-section of yet another modification showing a pair of V-shaped elements contacting each other at their apex thereof, and

2

FIG. 7 is a view of the separator or firewall of FIG. 3 before insertion, showing the lateral outward spring like effect of each of the planar legs.

Turning now to the drawing, a steel stud 10 of rectangular cross-section is provided with a pair of opposed narrow faces 11 and 12 disposed toward respective rooms and also with a pair of opposed wide faces 13 and 14 disposed between the wall partitions 15 (FIG. 2).

The studs 10 are preferably made from sheet metal, preferably steel, but studs made of glass fiber or asbestos plastic compositions are operable.

The studs are provided with rectangular apertures 16 adapted to receive hooks disposed on shelves or other structural elements.

As shown in FIG. 1, a firewall 17 is provided and it is disposed diagonally within the stud 10 so that both opposed stud faces 10 and 11 as well as faces 13 and 14 are out of atmospheric communication with one another.

The panel 17 is of such width as to fit snugly and substantially hermetically in the opposed diagonal corners of the stud. To obtain this effect the width of the panel edge 18 is preferably slightly larger than the diagonal length of the cross-section of stud 10. Thus the panel 17 is bowed or curved slightly during insertion into the stud 10 and it springs into tight contact with the stud corners upon being fully inserted therein.

The stud 10 preferably is of butt weld construction having a butt weld line 19. However, seamless studs are also operable in this invention.

Turning to FIG. 2, an integral single sheet firewall panel 20 of unique design is provided. This panel 20 is provided with a diagonally disposed center section 21 at each end of which there is provided a lateral section 22 and 23 respectively. A leg 24 is provided integral with and at a right angle to section 22 and a second leg 25 is provided integral with and at a right angle to lateral section 23.

The legs 24 and 25 of firewall 20 are normally urged spring like outwardly, so that when the firewall 20 is inserted into the stud 10 a tight planar sealing effect is made between leg 24 and stud face 13 and leg 25 and stud face 14. Such a large contact area provides an effective seal against passage of smoke or flame. The firewall 20 permits use of both rows of apertures on each of the stud faces 13 and 14.

In FIG. 3, a firewall 30 also of single sheet construction is provided with a center lateral section 31 of about the narrow dimension of the stud 10. The firewall 30 is provided with an upright leg 31 integral with the center section 31 at one end and with a depending leg 32 integral with the center section at its other end. As shown in FIG. 7, legs 32 and 33 are bent to the dash lines shown when they are inserted into the rectangular member 13-14 so that when the firewall 30 is inserted in place an extra large area of hermetical contact is made. However the use of a firewall 30 is possible only where a pair of the non-opposed stud apertures are not to be used, since legs 32 and 33 are disposed over these apertures of stud faces 13 and 14.

FIGS. 4, 5 and 6 show a firewall construction made of a pair of sheet metal elements in contrast to the firewall of FIGS. 1, 2 and 3 wherein a single sheet metal firewall separator is employed.

In FIG. 4, a pair of substantially U-shaped sheet metal elements 40 and 41 are used. The element 40 is provided with a base 42 and sidewalls 43 and 44 and element 41 is provided with a base 45 and side walls 46 and 47.

The bases 42 and 45 are disposed in planar area contact and preferably are suitably spot welded at suitable intervals. The legs 43 and 44 of element 40 and the legs 46 and 47 of element 41 are provided with suitable

divergent springiness so that when the firewall is inserted into the stud, legs 43 and 46 engage stud wall 13 and legs 44 and 47 engage stud wall 14 in a substantially air-tight manner.

FIG. 5 shows use of modified U-shaped elements 50 and 51 wherein element 50 is provided with a horizontal base 52 and substantially vertical legs 53 and 54 secured respectively thereto. Leg 53 is provided with an integral oblique portion 53X and leg 54 is provided with a similar oblique portion 54X but disposed in an opposed urging 10 relationship to that of portion 53X.

Likewise element 51 is provided with depending vertical legs 56 and 57. Leg 56 is provided with an oblique portion 56X and leg 57 is provided with a corresponding oblique portion 57X but operating in springy effect in 15 opposition to leg portion 56X. Preferably base 52 is spot welded to base 55 and the welded unit is inserted into stud 10 with portion 54X and 53X moved toward one another also portion 56X moved toward portion 57X. Thus upon insertion into stud 10 elements 53X 20 and 56X engage wall 13 with an urging force and elements 54X and 57X engage wall 14 also with an urging force to better effect a hermetic or air tight seal therebetween.

FIG. 6 shows a cross-section of yet another two piece firewall or separator wherein each sheet metal element is provided with a V-shape. The firewall of FIG. 6 comprises a first V-shaped element 60 having legs 61 and 62 and a second V-shaped element 63 having legs 64 and 65. The elements 60 and 61 engage one another in linear contact at their respective apices. Legs 61 and 62 are normally slightly more divergent beyond that necessary to merely touch walls 13 and 14. Similarly legs 64 and 65 are provided for a spring-like seizure of walls 13 and 14 by making legs 64 and 65 slightly more divergent 25

than necessary to effect mere touching contact with said walls.

Thus all separators or firewalls of this invention are preferably provided with means for effecting a spring-like seizure to the stud 10 so that a substantially hermetic seal is made between the separator and the stud.

This invention has been described with the use of several illustrative examples or embodiments but it is not to be limited to these illustrations.

I claim:

1. As an article of manufacture a tubular integral sheet metal partition stud for separating rooms, having apertures in the opposing sides thereof and a planar, non-apertured, flexible removeably disposed firewall disposed substantially diagonally-between and engaging in hermetically sealed relationship said opposing sides, said planar firewall being of a slightly larger dimension than the diagonal dimension of the stud so that the firewall is bent when inserted into said stud and upon release of the bent shape a spring tension engagement of said firewall and said stud is obtained.

2. The article of manufacture of claim 1 wherein the planar firewall is provided with angularly disposed planar portions adapted to seat in area planar relationship with the respective sides of said stud.
